UNITED STATES PATENT OFFICE.

WILLIAM MURPHY, OF ST. JOHN, NEW BRUNSWICK, CANADA.

CANVAS-STRETCHER FOR PICTURE-FRAMES.

SPECIFICATION forming part of Letters Patent No. 397,139, dated February 5, 1889.

Application filed March 26, 1888. Serial No. 268,540. (No model.)

To all whom it may concern:

Be it known that I, WILLIAM MURPHY, a citizen of the Dominion of Canada, residing at St. John, in the county of St. John and Province of New Brunswick, Canada, have invented certain new and useful Improvements in Canvas-Stretchers for Picture-Frames; and I do hereby declare the following to be a full, clear, and exact description of the invention, such as will enable others skilled in the art to which it appertains to make and use the same.

The object of this invention is to provide means for spreading picture-frames at the corners thereof in order to stretch the canvas thereon without allowing the parts of the frame to be displaced or tilted by the strain of the canvas. This object I attain by the construction and combination of parts hereinafter set forth and claimed.

In the accompanying drawings, Figure 1 represents a view in rear elevation of one corner of a canvas-holding frame provided with my invention and the canvas attached thereto, the frame being slightly broken away to show the tongue in position. Fig. 2 represents the same in perspective, not broken away, but slightly spread, the canvas being raised. Fig. 3 represents in detail perspective the mitered and saw-kerfed end of one of the parts of the said frame. Fig. 4 represents a detail perspective view of the slightly-bent tongue, the bending being exaggerated to make it more obvious, and the slotted wedge which straddles it, the latter being separated to show the slot. Fig. 5 represents a vertical section obliquely through the corner when the frame is lying flat.

A designates the canvas, and B and C represent contiguous parts of a picture-frame forming one corner, and having their ends mitered, as usual, to fit therewith. The canvas is attached, as usual, by making it overlap the outer faces of these parts B and C and tacking it thereon. In each of the mitered faces a saw-kerf, b, is made at right angles to the said face, the saw-kerf running lengthwise of said face and down the middle of it.

D designates a tongue or holding-plate of sheet metal, having arms or teeth d extending laterally with respect to the body of the plate and obliquely inward with respect to the frame. These arms or teeth enter the saw-

kerfs b, and the body of the tongue or holding plate enters the said saw-kerfs likewise when the parts B and C of the frame are brought together. When the frame is in its most contracted shape, the mitered ends touch each other and the tongue or holding-plate D is entirely embedded therein, except the upper corners, which are bent over slightly on the outer edges of the parts B and C; or, as in Fig. 1, only one of said upper corners may be thus bent, the other being so shaped as to be entirely embedded.

The plate or tongue D is bent on its middle longitudinal line, so as to be very broadly V-shaped in cross-section, with a slight inclination from the middle to the edge. The object of this shape is to resist more effectually the tilting strain of the canvas on the parts B and C. For this purpose the tongue or plate D is inserted with the convexity outward, so that the strain of the canvas will tend to straighten said tongue and will be resisted by the metal.

To spread the frame by separating the contiguous mitered faces of the parts B and C, I employ a wedge, E, which is pressed between the inner ends of said faces and slotted at e to straddle said plate or tongue. Each corner of the frame is provided with a tongue and a wedge constructed and combined as described, in order that the canvas may be stretched equally at all points and will lie smoothly everywhere. Of course other material may be substituted for canvas, and the frame may be used without any connection with pictures. Any flexible covering attached to it will be tightened by pressing the wedges in between the mitered faces of the frame, and the tongues will hold the parts of the latter against displacement. The wedges, being quite separable from the plates or tongues, may of course be withdrawn and replaced without interfering with the position of the tongues or plates in any way. These stretching and holding devices do not require any modification of the ordinary frame beyond the saw-kerfs. These last are not new, having been heretofore used with slotted holding plates or tongues which receive pins or studs in their slots, each plate being moreover in one piece with the corresponding wedge, in some instances at least.

Having thus described my invention, what I

claim as new, and desire to secure by Letters Patent, is—

1. A tongue or holding-plate, in combination with two contiguous parts of a frame, each part being saw-kerfed to receive one edge of said plate and the latter being bent at the middle in line with their meeting faces, for the purpose set forth.
2. A tongue or holding-plate, D, provided with oblique lateral teeth *d*, in combination with the parts B C of a frame, having in their mitered faces the saw-kerfs *b* to receive said teeth, and the body of said plate, substantially as set forth.
3. In combination with the parts B and C of the frame mitered and saw-kerfed, as described, the holding-plate or tongue D, bent in the middle and arranged with the convex side outward, said tongue or plate having lat-

eral arms or teeth *d*, which enter said saw-kerfs, for the purpose set forth.

4. The wedge E, having slot *e*, in combination with the tongue D, having lateral teeth *d*, and the parts B C of the frame, having saw-kerfs *b*, all arranged and operating substantially as set forth.

5. In combination with two contiguous parts of a frame having corresponding saw-kerfs in their faces, a metallic tongue fitting into said saw-kerfs, and a slotted wedge fitting between said faces and straddling said tongue, substantially as set forth.

In testimony whereof I affix my signature in presence of two witnesses.

WILLIAM MURPHY.
